TUBE FOR VENTILATING AIR

Birger Larkfeldt, Odensjo-Barnarp, and Lennart Widerby,
Jonkoping, Sweden, assignors to Aktiebolaget Svenska
Flaktfabriken, Necka, Sweden

Filed Aug. 22, 1974, Ser. No. 499,861

Claims priority, application Sweden Feb. 25, 1974

Term of patent 14 years

Int. Cl. D23—04

U.S. Cl. D23—163

FIG. 1

FIG. 2.

FIG. 4.

FIG. 3.

FIG. 5.

FIG. 1 is a front perspective view of a tube for ventilating air embodying our new design;

FIG. 2 is a top plan view thereof;

FIG. 3 is a front elevational view thereof;

FIG. 4 is an inverted plan view thereof; and

FIG. 5 is a side elevational view thereof.

FIGS. 2-5 are shown in reduced scale for ease of illustration.

We claim:

The ornamental design for a tube for ventilating air, substantially as shown and described.
